ROSSWELL W. THOMAS, OF BARTLESVILLE, OKLAHOMA, ASSIGNOR TO PHILLIPS PETROLEUM COMPANY, OF BARTLESVILLE, OKLAHOMA, A CORPORATION OF DELAWARE

CONSTANT PROPORTIONING GAS-MIXING APPARATUS

Application filed May 29, 1928. Serial No. 281,448.

This invention relates to improvements in constant proportioning mixer mechanism for use as a gas-air mixer for burners, or for carbureting or diluting gases of any kind.

5 One of the objects of the invention is to provide an apparatus capable of handling a plurality of gases at variable rates through changeable orifices, but at fixed differentials, and adapted to automatically maintain the 10 mixture in pre-determined (variable at the will of the operator) proportions, regardless of system pressure or rate of flow.

Another object is to furnish an apparatus 15 of this character with valve means actuated by differences in pressure of the gases handled; a part of said valve means being manually adjustable to facilitate accurate proportioning of the materials handled.

With the above objects outlined and with 20 further objects in view which will appear as the description proceeds, the invention includes the novel features hereinafter described in detail in connection with the accompanied drawing, and more especially pointed 25 out in the claims.

Referring to the drawing:

Fig. 1 is a top plan view of a preferred embodiment of the invention.

Fig. 2 is a vertical longitudinal section 30 taken on line 2—2 of Fig. 1.

In the drawing 1 designates a casing which may be formed of a base section 2 and a cover section 3 detachably connected together by any suitable means.

35 A pipe 4 is employed to lead air or any other suitable gas for the mixture into the chamber 5 of the casing and this pipe discharges into a housing 6, which is connected to the base 2 and communicates with the chamber 5.

A similar housing 7 is connected to the base and also to a mixture outlet 8, functioning to discharge the gases mixed in the apparatus to any suitable point of consumption.

40 A third housing 9, similar to the housings 6 and 7, is connected to the base 2 and it will be observed that the housings 6 and 9 are arranged parallel to the housing 7, but are of less length than the latter, for a purpose 45 hereinafter described.

A fuel gas inlet conduit 10 leads to the housing 9 and a valve structure 11 is interposed in this conduit. Said valve structure includes a valve head 12 designed to control orifices 13 in the valve structure, and the head is carried by stem 14 connected at its upper end to a diaphragm 15 which divides the valve casing into upper and lower compartments 16 and 17.

55 A pipe 18 places the chamber 16 in communication with the pipe 4.

It will be noted that the chamber 17 is in communication with the pipe 10 and as the chamber 16 communicates with pipe 4, it will be apparent that differences in pressure of the 60 gases passing through the pipes 4 and 10 will cause the diaphragm 15 to distort and move the valve head 12, so as to control the orifices 13.

65 For the purpose of steadyng the valve stem, the latter is provided intermediate its ends with a cross slot 19 which receives the curved ends 20 of levers 21 which are pivotally mounted on shafts 22 and are provided with weights 23, functioning to normally 70 shift the valve into closed position. The shafts on which the levers are mounted are arranged in the valve casing.

75 A second valve 24 is arranged within the casing 1 and this valve consists of an inverted cup having a marginal flange 25 surrounding its lower edge, the flange being slidably arranged on the base 2. This valve, as best shown in Figure 1, covers the housings 6, 7 and 9 and it may be shifted to control the 80 quantities of gases or mixed gases passing through said housings. This is accomplished by a pressure operated valve structure 26, which includes a diaphragm 27. The latter is connected to the valve 24 by a rod 28.

85 The pressure of the line 8 is transmitted to a chamber 29 of the valve structure 26 by means of a pipe 30, and a second chamber 31 of the valve structure 26 arranged at the opposite side of the diaphragm, communicates 90 with the chamber 5 by way of conduit 32.

95 From Fig. 2 it will be observed that the conduit 4 communicates with the chamber 5 through a passageway 33 and consequently the pressure in the conduit 4 is communicated 100

to one side of the diaphragm 27 while the pressure of conduit 8 is communicated to the opposite side of the diaphragm. It is apparent therefore, that differences in pressures in the conduits 4 and 8 will result in the shifting of the valve 24 to vary the quantities of the gases fed into the valve 24 from the conduits 4 and 10.

The outlet housing 7, as well as the housing 9 may be also controlled manually for regulating the quantity of mixture fed to the outlet pipe 8, and for this purpose one end of the valve 24 is provided with a horizontally disposed slot 34 that is cut in a metal strip 35 secured to the valve 24. A screw 36 extends through one wall of the housing 1 and has a threaded connection with the latter and the inner end of this screw has a swivel head 37 on which the valve 24 slides when it is shifted back and forth by the valve structure 26.

It will be apparent that when the screw 36 is moved inwardly or outwardly, the valve 24 will be shifted transversely and after an adjustment has been made the screw can be locked into position by a lock nut 38.

In using this device, assuming that it is employed as a mixing apparatus, fuel may be fed in through the pipe 10 and at the same time base gas or air will flow through pipe 4.

The mixed gases will exit through pipe 8.

The difference in pressures in the conduits 4 and 8 will result in the displacement of the diaphragm 27 and this will cause the rod 28 to shift the valve 24 to regulate the proportion of fuel gas to air. At the same time the differences in pressure in the conduit 8 and conduit 10 will cause displacement of the diaphragm 15 and in this way the valve 12 will be shifted to feed the proper quantity of fuel to the mixing apparatus.

As the valve 24 is subjected to uniform pressures on its opposite sides by means of the passageway 33, it will be observed that it is unnecessary to employ any special means for forcing the valve 24 against its seat.

The means connecting the end of the rod 28 to the valve 24 may be the same as that used to connect said valve to the screw 36. Those skilled in the art will recognize that the mechanism described may be used for various purposes and in numerous environments and changes may be made without departing from the spirit of the invention.

What I claim and desire to secure by Letters Patent is:

1. A gas mixing apparatus including a casing, a plurality of gas feed conduits connected to the casing, a mixture outlet connected to the casing, a valve controlling the quantity of gas passing from each of the gas feed conduits to the casing and also the gas mixture from the casing to the outlet conduit, and pressure-responsive means operable by differential pressure in certain of said conduits for shifting said valve.

2. A constant proportioning gas mixing apparatus, including a casing, a plurality of conduits for feeding gases to the casing, an outlet conduit for discharging the gas mixture from the casing, a valve structure in the casing for controlling the quantity of gas fed from each of the gas feed conduits to the gas outlet conduit, pressure responsive means operable by differential pressure in certain of said conduits for shifting said valve, said pressure responsive means comprising chambers separated by a movable element, passageways connecting said chambers to the last mentioned conduits, and other pressure responsive means operable by differential pressures in some of said conduits for varying the quantity of gas fed through one of said conduits.

3. A constant proportioning mixing apparatus including the casing, a plurality of gas feeding conduits communicating with the casing, a mixed gas outlet conduit communicating with the casing, a valve structure in the casing for controlling the quantities of gas passed from each of the gas feeding conduits to the mixture outlet conduit, pressure responsive means operable by differential pressures in certain of said conduits for shifting the valve, and manually controlled means for shifting the valve.

4. A constant proportioning gas mixing apparatus, including a casing, a plurality of gas conduits for feeding gas to the casing, a mixed gas outlet conduit also communicating with the casing, a valve structure in the casing for controlling the quantities of gases passed from the gas feeding conduits to the mixed gas outlet conduit, pressure responsive means operable by differential pressures in certain of said conduits for shifting said valve structure, pressure responsive means operable by differential pressures in certain of said conduits for varying the quantity of gas passed through one of said conduits, and manumotive means for shifting the first mentioned valve structure.

5. A constant proportioning gas mixing mechanism, including a casing, a gas feeding conduit communicating with the casing at one point, a passageway placing another point of the casing in communication with said conduit, a second gas feed conduit communicating with the casing, a mixed gas outlet conduit communicating with the casing, a valve structure in the casing for controlling the passage of gases through the casing, said valve structure being so arranged as to operate without affecting said gas passageway, pressure responsive means operable by differential pressures in certain of said gas conduits for shifting said valve structure, and pressure responsive means operable by differential pressures in certain of said conduits for varying the quantity of gas fed to the casing through one of said conduits.

6. A constant proportioning gas mixing mechanism, including a casing, conduits for feeding a plurality of gases to the casing and for discharging mixed gases from the casing, a valve structure in the casing for regulating the passage of gases through the latter, pressure responsive means operable by differential pressures in certain of the conduits for shifting the valve structure, a threaded stem 10 extending through a wall of the casing and having a threaded connection with said wall, and means connecting the threaded stem to the valve structure, said last mentioned means permitting movements of the valve structure 15 at an angle to the threaded stem. 75
7. A constant proportioning gas mixing apparatus, including a casing, a plurality of gas feeding conduits and a gas mixture outlet conduit connected to the bottom of the casing, an inverted cupped shaped valve slide- 20 ably mounted on the bottom of the casing and having a marginal flange adapted to control the passage of gases from the feeding conduits into the casing, pressure responsive 25 means operable by differential pressures in certain of said conduits for shifting said valve, and pressure responsive means operable by differential pressures in certain of said conduits for varying the quantity of the gas 30 passed through one of said feed conduits. 80
8. A constant proportioning gas mixing apparatus, including a casing, a plurality of conduits for feeding gases to said casing, a conduit for discharging mixed gas from the 35 casing, a valve in the casing for controlling the quantities of gases passed from each of the feed conduits into the casing, a closed chamber, a diaphragm dividing the chamber into two gas-tight compartments, means op- 40 eratively connecting the diaphragm to said valve, the diaphragm being operable by differential pressures in certain of said conduits for shifting the valve, passageways placing the last mentioned conduits in communica- 45 tion with said chambers, and a diaphragm controlled valve operable by differential pressures in certain of said conduits for varying the amount of gas fed through one of said conduits. 95
9. A gas mixing apparatus, including a casing, a plurality of gas feed conduits connected to the casing, a mixture outlet connected to the casing, a valve controlling the quantity of gas passing from each of the gas 55 feed conduits to the casing, and also the gas from the casing to the mixture outlet, and pressure responsive means operable by differential pressures in one of said conduits and said mixture outlet for shifting said valve. 100
10. A gas mixing apparatus including a casing, a plurality of gas feed conduits connected to the casing, a mixture outlet connected to the casing, a valve controlling the quantity of gas passing from each of the gas 65 feed conduits to the casing and also the gas 105
- mixture from the casing to the outlet conduit, pressure responsive means operable by differential pressure in certain of said conduits for shifting said valve, said pressure responsive means comprising chambers separated by a movable element, and passageways connecting said chambers to the last mentioned conduits. 110
